SYNCHRONIZING APPARATUS

James W. Light, Dayton, Ohio, assignor to General Motors Corporation, Detroit, Mich., a corporation of Delaware

Application October 25, 1945, Serial No. 624,513

3 Claims. (Cl. 175—355)

1

This invention relates to apparatus for synchronizing or equalizing the speed of engine, for example, the engine of a multi-engine airplane.

The object of the invention is to provide a synchronizing apparatus which is reliable in operation and simple in construction which can be produced at relatively low cost.

Further objects and advantages of the present invention will be apparent from the following descriptions reference being had to the accompanying drawings wherein a preferred embodiment of the present invention is clearly shown.

In the drawings:

Fig. 1 is a diagram of the apparatus.

Fig. 2 is a side view, in the direction of arrow 2 of Fig. 1, of a device used to vary the governed speed of an electric motor.

Fig. 3 is a plan view of one of the units of the apparatus, the part in section being on the line 3—3 of Fig. 4.

Fig. 4 is a sectional view on the line 4—4 of Fig. 3.

Fig. 5 is a fragmentary, sectional view on the line 5—5 of Fig. 3.

Fig. 6 is a fragmentary, sectional view on the line 6—6 of Fig. 4.

Fig. 7 is a fragmentary, sectional view on the line 7—7 of Fig. 6.

Fig. 8 is a view on lines 8—8 of Figs. 1 and 4.

Fig. 9 is a sectional view on the line 9—9 of Fig. 8.

Figs. 10, 11, 12 and 13 are sectional views, taken respectively, on the lines 10—10, 11—11, 12—12 and 13—13 of Fig. 9.

Numerical 10 designates one engine of a multi-engine plane. Engine 10 drives a shaft 11 which drives a propeller 12. The speed of the engine is controlled by changing the pitch of the propeller blades by mechanism contained within the propeller hub 13. This mechanism may be of the type shown in the Blanchard and MacNeil Patent No. 2,307,101, issued January 5, 1943. This patent discloses a speed responsive apparatus within the hub for controlling the blade angle to maintain a governed speed which may be varied by a device which includes a lever 14 adjustable about the axis of the shaft 11 but not rotatable therewith. Lever 14 may be manually actuated by a pilot's speed controlling lever 15 pivoted at 16 and connected by link 17 with lever 14. For purposes of synchronization, the lever 14 is operated automatically by a mechanism which includes a link 18 connecting lever 14 with a lever 19 connected by a friction clutch 20 connected by shaft 21 with

2

a speed reducing gearing 22 driven by an electric motor 25 which is provided with field windings 23 and 24 which may be selectively energized, in order that the motor may operate in one of two directions.

The field windings 23 and 24 are connected respectively by wires 27 and 28 with pairs of relay contacts 29 and 30 respectively. One contact 29 and one contact 30 are mounted, respectively, on 10 spring blades 31 and 32 fixed at their left ends and connected by a wire 33 and switch 34 and wire 35 with a battery 36. The motor 25 will operate in one direction or the other, depending upon which pair of relay contacts 29 or 30 are closed.

15 The spring blades 31 and 32 support armatures 41 and 42, respectively, adjacent magnet cores 43 and 44, respectively, which are surrounded by magnet coils 45 and 46, respectively, paralleled by condensers 47 and 48, respectively. Numeral 49 designates the relay having contacts 29 and 20 numeral 50 designates the relay having contacts 30.

As shown in Fig. 1, the equalization of engine speed is effected by causing the speed of each 25 engine to conform to a speed set by a master electric motor whose governed speed can be regulated. The master electric motor 60 which drives a shaft 61 has a series field winding 62 connected with the non-grounded commutator brush 63 and 30 with a brush 64 engaging a slip ring 65 driven by shaft 61 and connected by wire 66 with a spring blade 67 fixed at 68 and carrying a contact 69 engageable with a contact 70 carried by a spring blade 71 attached to a fixed terminal 72 connected by wire 73 connected with a slip ring 74 driven by shaft 61 and engaged by brush 75 which is connected with battery 36 by a switch 76, wire 77 and wire 35. The terminals 68 and 72, which together with the contacts and blades are 35 mounted on a non-conducting disc 78 driven by shaft 61 are connected in parallel with a minimum speed controlling resistance 79 and with a condenser 80 in series with a resistance 81 functioning to reduce sparking at contacts 69 and 70.

At a certain speed which can be adjusted in the manner to be described, contact 70 separates from contact 69 due to centrifugal force acting upon a weight 82 which may be attached, if 50 necessary, to the free end of spring blade 71. As indicated by the arrow 71a in Fig. 2, blade 71 biases contact 70 toward the right. As indicated by arrow 67a, blade 67 biases contact 69 toward the left end. By varying the initial position of 55 the blade 67, the speed at which contact 70 will

separate from contact 69 can be varied. To vary the position of blade 67 it is connected by link 85 with a lever 86 fixed to a shaft 87 supported by bearing brackets 88 attached to plate 78. Shaft 87 supports an arm 89 carrying button 90 whose axis coincides with the axis of shaft 61. Button 90 is engaged by a screw 91 threaded through a fixed support 92. If the screw 91 is turned so that it moves down in Fig. 2, blade 67 will be pulled toward the right, thereby allowing blade 71 to move toward the right, thereby reducing its tension or bias in that direction. Therefore the speed at which contact 70 will separate from contact 69 will be relatively low. If screw 91 is turned in the direction so that it moves up in Fig. 2, the opposite effect is obtained, that is, speed at which the contact 70 will separate from contact 69 will be increased. The electric motor with its speed controlling mechanism is not the subject of this application as this type of governed speed motor can be obtained on the market. It is understood that this motor is merely a typical example of a governed speed motor which may be used with the present invention. The screw 91 is turned by a flexible cable not shown having a control knob located within the convenient reach of the pilot who can set the governed speed at which all the engines of his plane are synchronized.

The shaft 61 drives slip rings 100, 101, 102 and 103 connected respectively by conductors 104, 107, 106 and 105 with certain bars of a commutator 110, said bars being marked respectively B, I, G, D, said commutator having a plurality of a series of the bars so marked. For example, as shown in Fig. 8, the commutator may have 30 bars separated by insulation, thereby providing five of each of the bars B, I, G and D with bars 108 and 109 not connected by any slip ring. The end faces of the commutator bars are engaged by brush 120 supported by a non-conducting arm 121 driven by a shaft 122 carrying a slip ring 123 connected with brush 120 and engaged by a brush 123a connected to a condenser 124 which is grounded. Shaft 122 is driven by a synchronous three-phase motor 125 connected with a three-phase generator 126 having a permanent field magnet 127 driven by the engine 10 through gears 128 and 129.

The shafts 61 and 122 rotate in the same direction, for example, clockwise as viewed toward the left as indicated by arrow 61a. If the speed of shaft 122 equals the speed of the shaft 61 neither of the relays 49, 50 is energized. If the speed of the shaft 122 exceeds the speed of shaft 61, the brush 120 moves relatively to the commutator 110 in the direction indicated by arrow 120a. Therefore the brush 120 will contact a commutator bar B in advance of contacting a bar blank 109 in advance of contacting an increase pitch bar I. Whenever the bars B are contacted by brush 120, the condenser 124 is connected with the battery and is charged through the following circuit. Battery 36, wire 35, switch 34, brush 100a, ring 100, wire 104, bar B, brush 120, ring 123, brush 123a, condenser 124. The charging of the condenser is followed by discharge thereof through the following circuit: When the brush 120 contacts bars I, a discharge circuit is as follows: Condenser 124, brush 123a, ring 123, brush 120, bar I, wire 107, ring 101, brush 101a, winding 45 of relay 49. The relay 49 momentarily closes contacts 29, thereby causing motor 25 to be connected with the battery through the following circuit: Bat-

tery 36, wire 35, switch 34, wire 33, blade 31, contact 29, wire 27, field winding 23 and armature of motor 25. This causes arm 19 to be turned clockwise and lever 14 to be turned counterclockwise in the direction of arrow 14i which is in the direction to increase the pitch of the propeller blade thereby reducing the speed of the engine 10. The greater the over-speed error, the more frequently will the condenser 124 be charged 10 and then discharged through the relay winding 45. Therefore, the more frequent will be the operations of the motor 25 to correct the speed error by shifting the governor adjusting lever 14 in the direction to increase blade angle. As the 15 correction is made, the engine speed is reduced so that the charging of the condenser 124 and the discharge thereof through relay winding 45 becomes less frequent. In other words, the less the speed error, the less frequent will be the increments of correction of the speed error. Therefore the tendency to over-correct the speed error is minimized. After the brush 120 contacts bar I to effect operation of relay 49 through discharge of condenser 124, it next contacts bar G which is grounded by wire 106, ring 102 and brush 102a. Therefore, there will be no condenser charge carried over into the succeeding decrease pitch bar D which is associated with the engine speed increasing section of the apparatus.

Conversely when the shaft 122 rotates at a speed less than shaft 61, relative motion between the brush 120 and the commutator 110 will be that indicated by arrow 120b. Therefore the charging of the condenser when the brush 120 contacts bars B will be followed by discharge of the condenser when the brush contacts decrease bars D through the following circuit: Condenser 124, brush 123a, ring 123, brush 120, bars D, wire 105, ring 103, brush 103a, magnet winding 46 of relay 50. The contacts 30 of relay 50 will close in order to connect the motor 25 with the battery 36 through the following circuit: Battery 36, wire 35, switch 34, wire 33, blade 32, contacts 30, wire 28, field winding 24 and armature of motor 25. The motor 25 will then rotate the arm 19 counterclockwise in order to move the governor adjusting lever 14 clockwise or in the direction of arrow 14d for the purpose of increasing engine speed by decreasing blade angle.

As over-speed or under-speed increases, there will come a time when the rate of relative motion between the brush 120 and the commutator 110 attains a value such that the frequency of discharges of the condenser 124 is such that contacts of either relay remain closed due to the lag which is inherent in the relay. The time lag can be increased in different ways, for example, the relay cores 43 and 44 can be provided with copper slugs or rings 43a, 44a, respectively, or the condensers 47 and 48, respectively, can be used in parallel with the windings 45 and 46 respectively. The function of these condensers is to receive a charge concurrently with the energization of the relay magnet windings and then discharge through the windings as the discharge of the condenser 124 reaches completion. In this way, the relay contacts can be maintained closed upon the attainment of a certain difference in the speed of rotation of the shafts 61 and 122. Therefore, the servo-motor 25 will operate continuously to effect the correction of the speed error of a certain magnitude. Then, as the speed error is reduced, continuous operation of the servo-

motor 25 is followed by an intermittent operation of diminishing frequency as the speed error approaches zero.

Instead of using lever 15 to override the control by the synchronizing apparatus, servomotor 25 can be rendered operative independently of the synchronizer. This is effected by movement of a switch handle 130 in either direction against the action of centering springs 131 in order to close contacts 132 which would reconnect battery 36 with motor field winding 23 or to close contacts 133 which would connect battery 36 with motor field winding 24.

In a multi-engine installation, four engines, for example, each engine will be provided with the apparatus shown in Fig. 1 except that there will be one master motor 60 for the four synchronizing apparatuses and one storage battery in an installation where each of the four engines drives a generator for charging the battery. Figs. 3 and 4 show a unitary construction for use in synchronizing four engines. There is a base 140 to which the master motor 60 is attached. A cable 141 extends from the motor to a speed adjusting knob not shown which controls the adjusting screw 91 of Fig. 1. As shown in Fig. 4, motor 60 drives a centrally located pinion 142 engaged by idle gears 143 which are rotatably supported by bearings 144 fastened to the frame 140 by screws 145. Gears 143 mesh with gears 146, each one of which drives a shaft 147 journaled in bearings 148 provided by the frame 140. Each shaft 147 carries the slip rings 100-103 and the bars of the commutator 110. Each shaft 147 is in alignment with the shaft 122 of a synchronous electric motor 125 which rotates a non-conducting arm 121 supporting a brush 120 connected by a strap 120s with the slip ring 123 which is engaged by brush 123a. Figs. 6 and 7 show the manner in which the brushes 100a to 103a are supported. Each brush is slidably supported by a metallic sleeve 150 supported by non-conducting bracket 151 attached by screws 152 to the base 140. A spring 153 within the sleeve 150 urges a brush toward a slip ring. The motors 125 are secured to the base 140 by screws 155 (Fig. 4) each of which passes through motor end frame 156, field frame 157, end frame 158 and spacer sleeve 159. The motors are enclosed by a cover 160 and gears are enclosed by cover 161. These covers are attached to the frame 140 in a similar manner. For example, the cover 161, as shown in Fig. 5, is secured to the base 140, by screws 162 passing through the cover and through spacer sleeves 163 and threaded into bosses 164 out of the base or frame. The cover 160 is secured to the base in a similar manner.

The commutator 110, as shown in Figs. 8 and 9, has a non-conducting hub 170 of cylindrical formation from which there extends an annular flange 171 received by a notch 172 in each of the commutator bars indicated by the various letters and numerals heretofore mentioned. As shown in Fig. 8, the bars are spaced by non-conducting segments 173 preferably of mica. The bars and segments are secured around the hub 170 by a non-conducting sleeve 174 which is surrounded by a metal band which after assembly, is divided into the slip rings 100, 101, 102 and 103. The band providing the slip rings and the non-conducting band 174 are secured to the bars by metal pins serving the functions of the conductors 104, 105, 106 and 107 of Fig. 1. Fig. 10, which is a section through slip ring 100, shows metal pins p104 connecting the ring 100 with

the bars marked B in Fig. 8. Fig. 11, which is a section through the ring 101, shows pins p107 connecting ring 101 with the bars marked I in Fig. 8. Fig. 12, which is a section through ring 102, shows pins p106 connecting ring 102 with the bars marked G in Fig. 8. Fig. 13, which is a section through ring 103, shows pins p105 connecting ring 103 with the bars marked D in Fig. 8.

10 In case of a two engine plane where the requirement is to maintain the engine speeds equal to each other rather than to a standard speed, the master motor 60 could be eliminated. Instead, one of the engines would be connected with the shaft 61 and the other engine would be provided with a synchronizing apparatus as shown minus the master motor.

15 The present invention is not limited in its use to the synchronization of airplane engines but may be used to synchronize various types of prime movers. In case of steam engines or turbines operating electric generators, for example, the master motor 60 would be adjusted to conform to a standard frequency of electric current such as 60 cycles. The servo-motor 25 associated with each engine would control the engine governing mechanism in order that its governed speed would conform to a speed set by the master motor.

20 While the embodiment of the present invention as herein disclosed, constitutes a preferred form, it is to be understood that other forms might be adopted, all coming within the scope of the claims which follow.

25 30 What is claimed is as follows:

35 1. In a synchronizing apparatus having means for effecting decrease and increase adjustment of engine speed to agree with a reference speed and means for comparing the engine speed with the reference speed and introducing a proper correction in character and amount to the respective engine adjusting means, said comparing means comprising a rotating contact brush driven in proportion to engine speed, a condenser having one plate constantly connected with said brush and a second plate connected to ground, a rotating commutator and slip ring assembly driven in proportion to the reference speed, said commutator having a plurality of 40 contact bars adapted to be sequentially engaged by the said brush upon differentials of brush and commutator rotation, the contact bars of said commutator being arranged in a plurality of groups of bars, means joining a first bar of 45 each group to a common slip-ring for connection to a current source, means joining a second bar of each group to a second common slip-ring for connection to an engine decrease speed adjusting means, means joining a third bar of each 50 group to a third common slip-ring for connection to an engine increase speed adjusting means, and means joining a fourth bar of each group to a fourth common slip-ring for connection to ground, means for connecting the separate slip-rings respectively with a current source, with an engine decrease speed adjusting means, with an engine increase speed adjusting means, and with ground, the sequence of bars in each group being such that differentials in rotation of the 55 brush and the commutator will effect movement of the brush over the bars to first connect the condenser with the current source and then connect the condenser with one of the engine speed adjusting means, and then connect the condenser with a grounding bar before connecting the con- 60 65 70 75

denser with the other engine speed adjusting means.

2. In a synchronizing apparatus for shafts of plural engines whose speeds are to be controlled to agree with a fixed speed shaft by means adjusting the speed of the engines to match the speed of the fixed speed shaft, the combination comprising means for sensing the character and amount of speed error for any engine and for signalling the character and amount of correction to be made, said sensing means including a plurality of commutator assemblies equal in number to the number of engines to be controlled, each commutator assembly including a set of contact bars, each set having a first bar for connection with a current source, a second bar of each set for connection with an engine decrease speed adjusting means, a third bar of each set for connection with an engine increase speed adjusting means, and a fourth bar of each set for connection with a common ground, a plurality of slip rings each electrically connected with like bars of each set, means coincidentally driving all of the commutator assemblies at a speed in proportion to that of the fixed speed shaft, a brush for each commutator assembly continuously rotatable in proportion to the speed of a separate engine shaft and adapted to engage the bars of the associated commutator assembly, a plurality of condensers each continuously connected between ground and one of said brushes, and means acting upon relative rotation between each brush and its associated commutator for effecting the sequence of first connecting the condenser to the current source for charging the condenser, then connecting the condenser to one of the speed adjusting means to apply the proper correction to the speed of the respective engine, and then connecting the condenser to a grounding connection for completely discharging the condenser before connecting the condenser to the speed adjusting means of improper correction.

3. In rotatable apparatus controlled by reversible speed decrease and speed increase devices upon differential rotation of an adjustable speed member and a fixed speed member, the combination with said members of means for rotating the adjustable speed member in proportion to the rotative speed of the rotatable apparatus, means for rotating the fixed speed member in proportion to a reference speed, a continuously rotating brush driven by said adjustable member, a condenser connected between said brush and ground, said fixed speed member comprising a continuously rotating commutator having a plurality of sets of contact bars adapted to be individually engaged by said brush, each of said sets including a group of three consecutively arranged

mutually insulated bars and a single bar spaced therefrom and equally spaced from a like group of three contact bars in an adjacent set, a plurality of slip rings and means connecting each ring with all bars of like position in all sets, means connecting said single bar of each set through its connecting slip ring with a current source for charging said condenser when the brush engages any one of said single spaced bars, means connecting an end bar of each group of three as a second bar of said set through its connecting slip ring with a control means for the speed decrease device, means connecting the other end bar of each group of three as a third bar of said set through its connecting slip ring with a control means for the speed increase device, and means connecting the middle bar of each group of three as a fourth bar of said set through its connecting slip ring with a common ground connection for completely discharging said condenser when the brush engages any one of the said fourth bars, the sequence of the four bars of each set being such that relative rotation between the said adjustable speed member and the said fixed speed member effects engagement between said brush and said single spaced bar to connect said condenser with the current source for charging the condenser, and such that continued relative rotation between said members effects engagement between said brush and the said second or third bar to connect said charged condenser with either the speed decrease control means or the speed increase control means respectively, and that further continued relative rotation after said condenser has been connected with either the speed decrease control means or the speed increase control means effects engagement of said brush with the said fourth bar for completely discharging the condenser to ground before the condenser is connected upon further continued rotation to either the speed increase control means or the speed decrease control means respectively.
